BUTTON COVER

James Adams Van Meter, Van Nuys, Calif., assignor of one-tenth each to Vickie Van Meter and Baron Van Meter, both from Van Nuys, Calif., and Mickey Craig, Sunland, Calif.

Filed Mar. 21, 1961, Ser. No. 97,381
8 Claims. (Cl. 24—108)

This invention relates to a button cover, and more particularly to a decoration cover usable with a garment having a button and a button hole therefor for decorating the garment by removably securing an ornamental article to the button which is visible from the exterior of the garment while covering the original button, and for simulating a cufflink on a conventional button receiving cuff.

More particularly, this invention provides a button cover having an ornamental article, such as generally used and including polished semi-precious or other stone, with a gripping means attached thereto, the gripping means being insertable through a button hole for gripping the button, while the ornamental article is visible from the exterior to decorate the garment. Besides being used to mount the usual ornament, it is particularly useful for collectors of minerals and semi-precious stones for displaying their collection or putting it to practical use.

An object of this invention is to provide a new and improved button cover in which the conventional button on a garment is covered and disguised by an ornamental article, yet which, when removed leaves the button useful, with its buttonhole, in conventional manner.

A further object of this invention is to provide a new and improved button cover which is applicable to a conventional buttoned cuff to simulate the appearance of a cuff link having an ornamental article secured thereto.

A further object of this invention is to provide a new and improved button cover which provides new and improved resilient gripping means for gripping the existing button of the garment by which the ornamental article is easily and readily removably secured to the button.

Yet another object of this invention is to provide a new and improved button cover in which the gripping means thereof is easily and readily inserted through the existing button hole of the garment for access to the button thereof.

Another object of this invention is to provide a new and improved button cover which is removably securable to the garment portion having the button hole and selectively securable to the button wherein the button cover is retained upon the button hole portion of the garment during engagement and disengagement of the button.

An object of this invention is to provide a new and improved button cover which is economical to manufacture and capable of mass production.

A general object of this invention is to provide a new and improved button cover of the character described which generally overcomes disadvantages of prior means and methods heretofore intended to accomplish generally similar purposes.

These and other objects of this invention will be more apparent from the following detailed description, drawings and appended claims.

In the drawings:

FIGURE 1 is a horizontal cross sectional view taken

2

substantially through the center line of a button hole of a garment, herein illustrated as the cuff of a shirt, blouse, or the like;

FIGURE 2 is a rear side view of the button cover of this invention;

FIGURE 3 is a fragmentary vertical cross sectional view taken substantially along the lines 3—3 of FIGURE 2;

FIGURE 4 is a side view, similar to FIGURE 2, illustrating a modified embodiment of this invention; and

FIGURE 5 is a vertical cross sectional view taken substantially along the lines 5—5 of FIGURE 4.

Referring in detail to the drawings, there is shown, by way of illustration but not of limitation, a button cover designed and constructed in accordance with this invention and generally designated by the number 10. The button cover 10 is herein illustrated as applied to a button 11, sewn or otherwise secured to a garment generally designated by the numeral 12. The garment 12 is illustrated herein as for example, a cuff of a shirt or blouse and is shown in cross section in FIGURE 1, wherein a button hole 13 is provided for receiving the button 11 to secure the cuff in conventional manner.

The button cover 10 generally comprises a base 14 of relatively rigid material and having an ornamental article, such as a semi-precious stone or other ornamental jewelry indicated by the numeral 16, secured by cementing or the like to one side 17 thereof.

The ornamental article 16 is preferably slabbed on one side prior to securement to the base 14, to provide a relatively flat surface for the purpose of cementing. However, it is to be recognized that an article 16 having an irregular back surface may be advantageously secured to the side 17 of the base by using a base of relatively soft ductile material which may be deformed somewhat to conform to the configuration of the article. Further an increased amount of cement may be used to fill gaps existing between the base and the stone.

A button gripping means, insertable through the button hole 13, and generally designated by the numeral 18 is secured to an opposite side 15 of the base 14. The button gripping means 18 includes an elongated, relatively rigid member 19 having outer ends 21 and 22 which are outwardly turned back. A pair of elongated, flexible, resilient members 23 and 24, in the form of expandable coiled springs are stretched across the member 19 from the ends 21 and 22, in spaced parallel relationship. Each spring 23, 24 is secured to each turned back end 21 and 22 by engagement of their ends 26 and 27 in apertures 28 provided in each turned back end.

Optionally, as best seen in FIGURE 4, a pair of hooks 29 may be provided in each turned back end designated in FIGURE 4 as 21' and 22'.

By virtue of the turned back ends 21 and 22, the springs 23 and 24 are in spaced parallel relationship to the remainder of the elongated member 19, for a purpose which will be hereinafter described.

The elongated member 19 is additionally provided with an offset portion 31 which is offset from the center thereof to form short and long portions or arms 32 and 33, respectively, of the elongated member 19. The portions or arms 32, 33 are spaced from the base 14 so as to provide space between the button gripping means 18 and

the base 14 in which the material of the garment 12 surrounding the button hole 13 resides when the button cover 10 is placed thereon. The arm 33 is longer than the arm 32 so that the elongated member 19 may be conveniently inserted through the button hole 13 which is normally appreciably shorter than the overall length of the elongated member 19. The elongated member 19 is secured at the offset 31 to a central portion of the base 14 by a fastener such as a rivet 36. Optionally, the offset portion 31 may be secured to the base 14 by soldering, spot welding, or the like.

To install the button cover 10 on the garment 12, the button gripping means 18 is inserted through the button hole 13 by inserting the longer arm 33 first, after which the shorter arm 32 may be conveniently slipped into the button hole with the garment portion surrounding the button hole 13 residing in the space between the offset arms 32 and 33 and the base 14, as seen in FIGURE 1.

The springs 23 and 24, in spaced parallel relationship, form an auxiliary button hole whereby the springs are laterally displaceable and expandable to facilitate insertion of the button 11, when turned edgewise, into a position residing between the springs 23 and 24 and the main portion of the elongated member 19. The button is held by the springs 23, 24 when the button is again turned to its normal flat relationship. The springs 23 and 24 then resume their normal taut position to span the fastening means for the button 11 such as the thread indicated by the numeral 34.

Optionally, the arms 32 and 33 of the elongated member 19 may be formed integrally with the base, as indicated in FIGURES 4 and 5. In these figures, like parts are referred to by like numbers which are primed. The base 14' of the instant embodiment 10' is secured to an ornamental article 16', similar to the ornamental article 16, and is similarly secured by cementing or the like. The base 14' includes a relatively short arm 32' and a relatively long arm 33'.

Springs 23' and 24' are secured to the turned back end or tab 21' and 22' of the arms 33' and 32', respectively, each turned back end or tab having a pair of hooks 29, or optionally apertures 28 to which the ends of the springs 23' and 24' are removably secured.

As in the previous embodiment, the arms 32' and 33' are offset from the base 14' to form spaces 37 and 38, respectively, in which the material surrounding the button hole of the garment 12 may reside when the button cover 10' is inserted into the button hole 13 of the garment.

It will now be more clearly seen from the foregoing description that when the button cover 10 is inserted into the button hole 13 to place the button gripping means 18 against the inner surface of the garment 12, the button 11 may be inserted through the springs to reside between the springs and the base 14 or 14' to close the cuff of the garment, thus giving an appearance of a semi-precious stone 16 secured on the exterior of the garment or of a cuff link. The devices 10 and 10' may be also used to cover the front button of a garment in a similar manner as for the button of the cuff, or to complement it, so as to decorate the front panel of the garment. Any ornamental article may be used for securing to the exterior of the bases 14 and 14', such as semi-precious or precious stones in their natural but polished state as they appear after slabbing and tumbling to produce a very effective and ornamental decoration for garments. In the event a precious stone is used, a jeweler's mount is preferably used.

While there is herein shown and described what is conceived to be the most practical and preferred embodiments of this invention, it is recognized that departures may be made therefrom within the scope of this invention which is not to be limited to the details disclosed

herein but is to be accorded the full scope of the claims so as to embrace any and all equivalent devices.

What is claimed is:

1. A button cover for a button secured by fastening means to a garment having an overlying portion with a button hole therein, comprising: a base having a pair of opposing arms extending from one side thereof and offset in spaced substantially parallel relationship thereto, one of said arms being appreciably longer than the other of said arms, each arm having tab means extending outwardly therefrom; an ornamental article secured to an opposite side of said base and being appreciably larger than the button hole so that it will not pass through the button hole; a pair of parallel flexible resilient members spaced apart a distance less than the width of said button, each resilient member having an end secured to one of said tab means so as to be in spaced parallel relationship to said arms; said arms being selectively extensible through the button hole so as to position said arms adjacent to the inner surface of said overlying portion and to said button, and to position said base adjacent to the outer surface of said overlying portion, said resilient member being laterally and longitudinally expandable so as to receive the button therethrough in edgewise relationship for positioning the button in flat relationship between said resilient members and said arms with said fastening means residing between said resilient members.
2. A button cover as defined in claim 1 wherein each of said tab means includes an outwardly turned back end on one of said arms and a pair of spaced hook means on each said turned back end, the ends of each end of said resilient member being removably secured to one of said hook means of each of said tab means.
3. A button cover as defined in claim 2 wherein each resilient member comprises an expandable coil spring having opposing ends removably engaging said hook means.
4. A button cover for a button secured by fastening means to a garment having a button hole therein comprising:
  - a planar base;
  - an arm extending beyond said base substantially in a plane parallel to said base;
  - first securing means at the end of said arm extending outwardly thereof;
  - second securing means extending outwardly of said base in the same direction as said first securing means;
  - a pair of resilient members extending side by side between said securing means and secured thereto;
  - said arm being adapted to be inserted into a button hole;
  - said resilient members being spaced apart a distance less than the flat width of a button;
  - said button being insertable edgewise between said resilient members and thereafter secured between said members and said arm with said fastening means extending between said members while said button is in flat position.
5. A button cover as defined in claim 4 wherein each securing means includes a pair of spaced apertures and each resilient member includes ends removably engaging one of said apertures for securing said resilient members to said securing means.
6. A button cover as defined in claim 4 wherein said base member has an ornamental article secured thereto.
7. A button cover as defined in claim 4 wherein said arm is offset from said base for providing a space between said base and said arms for receiving garment material surrounding said button hole.
8. A button cover as defined in claim 4 wherein each of said resilient members comprise an elongated coil spring capable of lateral and longitudinal flexing during edgewise insertion of said button between said springs.
